UNITED STATES PATENT OFFICE.

PATRICK KILLPATRICK, OF HURON, SOUTH DAKOTA.

VENTILATING AND PERFUMING DEVICE.

1,032,912.

Specification of Letters Patent. Patented July 16, 1912.

Application filed May 4, 1911. Serial No. 624,985.

To all whom it may concern:

Be it known that I, PATRICK KILLPATRICK, a citizen of the United States, and a resident of Huron, county of Beadle, and State 5 of South Dakota, have invented certain new and useful Improvements in Ventilating and Perfuming Devices, of which the following is a specification.

My invention relates to means for ventilating and perfuming rooms, and it consists in the combinations, constructions, and arrangements herein described and claimed.

An object of my invention is to provide a device by means of which pure air may be supplied evenly to the various parts of a room.

A further object of my invention is to provide a device by means of which the natural perfumes of growing flowers may be supplied to the interior of a dwelling, hospital, or other building.

Other objects and advantages will appear from the following specification, and the novel features of the invention will be particularly pointed out in the appended claims.

My invention is illustrated in the accompanying drawings in which similar reference characters indicate like parts in the several views and in which—

Figure 1 is a front view of the distributing funnels. Fig. 2 is a side view of the motor for operating the funnels. Fig. 3 is a section through one of the distributing funnels. Fig. 4 is a side view of an intake funnel and fan therefor, and, Fig. 5 is a plan view of the parts shown in Fig. 4.

Referring particularly to Figs. 4 and 5, it will be seen that I have provided an intake funnel 1 which is disposed out doors 0 preferably in the vicinity of a flower bed or flowering tree (not shown). A tube 2 connects the funnel with a rotary fan 3 which may be driven by an electric motor 4, the motor and fan being mounted in a 5 suitable base 5. A pipe 6 connects with the casing 7 secured to the ceiling 8 of the room to be ventilated or perfumed. From the casing a tube 9 is suspended which terminates in two branches 10 and 11, each having 0 a ball bearing distributing funnel like that shown in Fig. 3. The distributing funnels each consist of a mouthpiece A screwed into a spherical shell B which is threaded 5 through the latter is a nipple D which is

flanged to support the collar and which enters one of the pipes 10 and 11 being held therein by a set screw E. The shell B has an extension b. Secured to the ceiling 8 is a motor 12 which drives a crank 13 carried 60 by the frame 14, through the medium of the belt 15. A pitman 16 is pivotally attached to the extension b of each funnel.

From the foregoing description of the various parts of the device, the operation 65 thereof may be readily understood. Fresh air and the perfume of flowers are drawn through the funnel 1 by the fan 3 and forced through the pipe 6, casing 7, pipe 9 and through the branches 10 and 11 out through 70 the distributing funnels A and A' which point in opposite directions. As the motor 12 turns the crank 13, the latter causes the funnels A and A' to oscillate to and fro on their ball bearing pivots such as that shown 75 at F in Fig. 3. This causes an even distribution of the perfumed air about the room.

I claim:

1. In a ventilating device, an air distributor comprising a spherical shell having 80 threaded openings, a mouth piece screwed in one opening, an integral extension of said spherical shell projecting therefrom on the opposite side from said mouth piece, a collar screwed in another opening, said 85 collar being provided with an inwardly turned flange, a nipple provided with an outwardly turned flange arranged to support the inwardly turned flange of said collar, and a suspension pipe arranged to receive one end of said nipple, said suspension pipe being provided with a set screw arranged to engage the nipple for securing it to the pipe.

2. In a ventilating device, an air distributor comprising a pendent tube, branches 95 therefrom at the lower ends thereof, a spherical shell at the end of each branch, a swivel connection from each shell to its branch for supporting the shell, a mouth 100 piece carried by each spherical shell on one side thereof, an extension on each shell on the opposite side from the mouth piece, said extensions pointing toward one another and serving as means for turning said shells 105 on their swivel connections.

PATRICK KILLPATRICK.
